UNITED STATES PATENT OFFICE

CONRAD SCHMIDT, OF SPOKANE, WASHINGTON.

PORTABLE ELECTRICALLY-HEATED RADIATOR.

1,141,888.

Specification of Letters Patent.

Patented June 1, 1915.

Application filed May 12, 1913. Serial No. 767,061.

To all whom it may concern:

Be it known that I, CONRAD SCHMIDT, a citizen of the United States, residing at Spokane, in the county of Spokane and

5 State of Washington, have invented a certain new and useful Improvement in Portable Electrically-Heated Radiators, of which the following is a full, clear, and exact description.

10 The object of this invention is to provide a portable heat radiator, in which water is heated by an electrical apparatus, and the temperature controlled as desired, it being possible to convert the water into steam, and 15 to superheat it when desired, as well as to use it at a lower temperature. Provision is also made for utilizing the radiator for cooking purposes.

The invention consists, in its preferred 20 form, of a portable tubular water-container and radiator, in and upon which the necessary electrical apparatus is mounted to supply heat in regulated or varied amounts, so that the apparatus as a whole may be 25 placed wherever desired and connected with a source of electric current, and used not only for heating but also for cooking purposes, as I will proceed now to explain and finally claim.

30 In the accompanying drawings illustrating the invention, in the several figures of which like parts are similarly designated, Figure 1 is a front elevation, with some parts in section and others broken away. 35 Fig. 2 is a horizontal section on line A B, Fig. 1, looking down. Fig. 3 is an elevation of the right-hand end of Fig. 1. Fig. 4 is a vertical section on line C D, Fig. 1. Fig. 5 is a plan view, and Fig. 6 is a vertical section of the insulated contact yoke of the rheostat.

The boiler 1 has the filling tube 2 which is supplied with any suitable closure 3.

4 is the steam drum, provided with a 45 safety valve 5, which may be of the spring-pressed ball variety, as shown in Fig. 1.

The boiler 1 and the drum 4 may be connected by any number of circulation and radiation tubes, and I prefer to use a centrally arranged series of relatively large tubes 6, flanked both front and rear by two or more series of smaller tubes 7 preferably arranged staggering. The larger tubes 6 may extend down into the boiler, as shown 55 in Fig. 4, so as to return also the condense

water from the drum to the boiler. The radiator may have the feet or stands 8 to support it in any desired position or location.

9 is a water glass or gage on the boiler. 60 Within the boiler 6 are the tubes 10 extending lengthwise thereof, and having their ends closed; and within these tubes are the electrical heaters, each herein shown as composed of a core 11, of suitable refractory 65 substance, such as asbestos, an encircling conducting heating coil 13, and a jacket 14 of refractory material, such as asbestos inclosing said heating coil. The coils of the heaters are connected in circuit at one end, as 70 by wires 15, and their other ends 12 are extended upwardly and coiled about a pair of porcelain cylinders or cores 16, vertically arranged at one end of the radiator, on any suitable brackets 17, and forming a pair of 75 rheostats.

The leading-in wires 18 are connected to a switch 19, having an operating device or key 20, and flexible wires 21 connect this switch with the insulated ends of a metallic 80 yoke 22, arranged in sliding contact with the coils of the rheostats. This contact yoke is provided with a hole 23 in its center and insulating blocks 23^x upon opposite sides of said hole to insulate the ends of the yoke 85 from its body, as shown in Figs. 5 and 6. The hole 23 serves to receive the end of a piston rod 24 carrying a piston 25 mounted to reciprocate in a cylinder 26 and normally drawn into said cylinder by means of a 90 spring 27. This cylinder 26 extends up into the heating drum 4 and its piston is exposed to the pressure contained in said heating drum, so that by increase of pressure the piston will be forced down into the cylinder 95 against the pressure of the spring and carry the contact yoke 22 down between and in contact with the coils of the rheostats. As pressure increases upon the increase of heat, the downward movement of the contact yoke 100 will cut in more or less of the rheostat coils and thus gradually reduce or vary the current passing to the heating coils and consequently vary the heating effect of the coils, and restore the proper or desired temperature of the radiator. The spring 27 acting upon the piston effects the return movement of the yoke upon the reduction of pressure in the radiator. The porcelain parts 16 may have the grooves 28 arranged facing one an-

other so as to allow the wires to give and thus insure contact when the contact yoke 22 passes over them.

The operation would seem to be obvious; 5 but it is proper to suggest that water is placed in the boiler to any desired level, and the proper connection made between the wires 18 and a source of electrical current, and the water thus heated. If it is desired 10 to convert the water into steam for steam heat, then the level of the water might be lower than if it were simply desired to heat by hot water radiation. When steam of a sufficient degree of heat and pressure is pro- 15 duced, the pressure will act upon the piston 25 and move it downward, thereby carrying with it the contact yoke so as to gradually cut in more or less of the rheostat coils. In this way the heating capacity of the radi- 20 ator is regulated automatically.

The radiator may be made and used as thus described, but its utility may be enhanced by the addition of a superheater 29, arranged in the drum, and a cooker 30, also 25 arranged in the drum, either or both of which may be used. The superheater may consist of an electric heating coil, suitably supported in the drum and connected in series with the heating element or coil 13 by 30 the wires 15. The cooker may comprise a porcelain or other non-conducting and refractory tray 31, suitably secured in the top of the drum and provided with suitable electric resistances 32, which are connected in 35 series with either the superheater or boiler-heater or both, or otherwise supplied with current. Switches 33 and 34 may be used to cut in and out the superheater and the cooker, respectively.

40 The electrical apparatus as here shown is designed for use in connection with the ordinary domestic electric lighting circuits.

Variations in the details of construction and arrangement are permissible within the 45 contemplation of the invention.

What I claim is:—

1. The combination with a portable tubular radiator, having a boiler and a steam drum or dome, a series of circulation and 50 radiation tubes connecting said boiler and steam drum or dome, an electric heater in said boiler, and a source of electric supply for said heater, of a rheostat connected in circuit between said heater and the source of 55 supply and including a movable contact piece, and means connected to said movable contact piece and exposed to and operable by variations of pressure in said steam drum or dome to move said contact piece over said 60 rheostat to gradually cut in or out more or less of the resistance of said rheostat and

thereby vary the current supplied to said electric heater to automatically regulate the heating capacity of the radiator in accordance with the temperature desired. 65

2. The combination with a portable radiator, having a boiler and a steam drum or dome, a series of circulation and radiation tubes connecting said boiler and steam drum or dome, electric heating elements arranged 70 in said boiler, and a source of electric supply for said heating elements, of a pair of rheostats having their resistance coils connected in circuit with said heating elements, a movable contact yoke connected with the source 75 of supply and engaging the coils of said rheostats, a spring supported piston to which said contact yoke is connected, and a cylinder for said piston opening into said steam drum or dome and exposing said piston to 80 the pressure therein, whereby said piston is caused to move said contact piece over said rheostats to gradually cut in or out more or less of the resistance coils thereof to vary 85 the amount of current supplied to said heating elements and thereby automatically regulating the heating capacity of said radiator in accordance with the temperature desired. 90

3. In a radiator of the type described, a boiler, an electric heating element arranged 95 in said boiler for heating water therein, a steam drum or dome communicating with said boiler, an electric heating element arranged in said steam drum or dome for superheating 100 the steam generated therein by said boiler and connected in series with the boiler heating element, an electric cooking element arranged in the upper part of said steam drum or dome and connected in series with 105 said heating elements, and switches interposed between said boiler heating element and said superheating and cooking elements for cutting in or out of circuit either or both 110 said superheating and cooking elements. 115

4. In a radiator of the type described, a boiler, a steam drum or dome communicating with said boiler, an electric heating element arranged in said boiler for heating the water therein and generating steam in said steam drum or dome, an electric cooking element arranged in the upper part of said steam drum or dome and connected in series with 110 said boiler heating element, and a switch interposed between said boiler heating element and said cooking element for cutting 115 in or out the circuit to said cooking element.

In testimony whereof I have hereunto set my hand this 28th day of April A. D. 1913.

CONRAD SCHMIDT.
